UNITED STATES PATENT OFFICE.

JULIAN SMIGIEL, OF HARTFORD, CONNECTICUT.

SOLDERING-TOOL.

1,273,281.

Specification of Letters Patent. Patented July 23, 1918.

Application filed March 30, 1918. Serial No. 225,636.

To all whom it may concern:

Be it known that I, JULIAN SMIGIEL, a citizen of Poland, residing at Hartford, county of Hartford, and State of Connecticut, cut, have invented certain new and useful Improvements in Soldering-Tools, of which the following is a specification.

This invention relates to improvements in soldering tools and particularly to those of 10 a self heating type.

The principal object is to provide a tool of the class described combined with an internal heater, fed by gasoline or like liquid fuel.

15 Another object of the invention is to provide means whereby the heater element may be rapidly and conveniently removed or inserted.

These and other like objects are attained 20 by the novel construction and combination of parts hereinafter described and shown in the accompanying drawing, forming a material part of this disclosure, and in which:—

Figure 1 is a partial side elevational and 25 vertical sectional view of a soldering tool made in accordance with the invention, and

Fig. 2 is a transverse sectional view taken on line 2—2 of Fig. 1.

The invention comprises a hollow cylindrical body 10, formed with a point 11, which may be of the usual chisel or diamond shape as preferred.

Adjoining the tubular body 10, is an enlarged globular extension 12, and extending 35 therefrom is the upper portion 14 of the implement, contracted at the neck 15, and formed with a boss 16, extending laterally out from one side, the central portion of the neck 15, having a plain bored circular opening 18, suited to receive a burner or torch 20, having a rounded imperforate end 21, while the main portion has formed through 40 it a plurality of perforations 22.

Vapor is supplied to the burner through 45 the hollow arm 24, connected by a pipe 25, with a reservoir 26, adapted to contain gasoline or other inflammable liquid, the same being entered through an opening at its upper end, normally covered by the cap 27.

50 Formed in the upper portion of the burner 20, is a valve seat (not shown) controlled by the screw-threaded stem 28, of a needle valve provided with a knurled head 29, by which it may be operated, the point of the valve 55 controlling the opening 30 formed through the burner.

In the extension 16 of the body, is formed a transverse slot or recess 32 in which is slidably received a block 33, provided with screw-threads 34 on its inner surface, adapted to engage with the screw-threads 35, upon the upper portion of the burner 20. 60

This block is operable by means of a stem 37, having at its outer end a pin 38, operable within a longitudinal slot 39, formed in the 65 end of a lever 40. This lever is pivoted on a pin 41, set in a bracket 42, formed integrally with the outer end of the body 14, the lower end of the lever terminating in an operative pad 44, by means of which the 70 block 33 may be withdrawn so as to clear the threads 35, allowing the burner to be removed.

A coiled tension spring 45 is attached at one end within a recess formed in the extension 16, and at the other end to the lever 40, the same normally maintaining the block in engagement with the screw-threads of the burner, the arrangement being such that as soon as liquid fuel is communicated from 80 the reservoir 26, to the burner 20 and the same ignited, the flame issuing from the perforations 22, fills the globular body 20 and communicates heat to the point 11, escape of smoke being provided for by the perforations 47. 85

In operation, the reservoir 26, having been filled with gasoline or the like, and the needle-valve properly adjusted to allow a certain amount to pass downward through 90 the opening 30, the torch or burner permits the gases to pass through, which upon being ignited are entered within the head by depressing the lever 44, releasing the block 33, which permits the ready engagement of 95 the burner within the body and which afterward may be rotated therein and adjusted due to the screw-thread connections.

Having thus described my invention, what I claim as new and desire to secure by 100 Letters Patent, is:

1. In a soldering tool, the combination with a hollow head, an applicator point formed therewith, and means for the entrance of a burner, of a perforate burner 105 tube engageable within said head, a liquid fuel holding reservoir connected with said burner, means for the control of fuel to said burner, a lever by which said burner may be engaged or released with respect to said 110 hollow body, and means for the escape of the products of combustion from said body.

2. In a soldering tool, the combination with a hollow head having an applicator point and a globular element formed therewith, said globular element being perforated, of a burner enterable opposite to said applicator point, said burner having screw-threads formed upon the outer surface, a block slidably engaged in said head adjacent to the opening through which said burner enters, a lever for operating said block, means for normally keeping said block in engagement with said thread, and means of supplying a liquid fuel to said burner.
3. In a soldering tool, the combination with a hollow perforate head having an applicator point formed therewith and a cen-

tral opening opposite to said point, of a burner adapted to use liquid fuel enterable through said opening, said burner being screw-threaded, of a screw-threaded block 20 slidably engaged transversely of said burner adjacent to said opening, means for normally holding said block in engagement with the threads of said burner, means whereby said block may be retracted from 25 said thread, hollow connections between said burner and said source of supply, and means for controlling said connections.

In testimony whereof I have affixed my signature.

JULIAN SMIGIEL.
